[57] CLAIM

The ornamental design for a pencil sharpener, as shown and described.

DESCRIPTION

FIG. 1 is a right front top perspective view of the pencil sharpener;
 FIG. 2 is a front view thereof;
 FIG. 3 is a rear view thereof;
 FIG. 4 is a right side view thereof;
 FIG. 5 is a left side view thereof;
 FIG. 6 is a top view thereof;
 FIG. 7 is a bottom view thereof; and,
 FIG. 8 is a left rear bottom view thereof. The broken lines showing an eraser and a portion of a pencil are for illustrative purposes only and form no part of the claimed design.

1 Claim, 2 Drawing Sheets

FIG. 1.FIG. 2.FIG. 3.FIG. 4.FIG. 5.

FIG. 6.

FIG. 7.

FIG. 8.
